TYPEWRITING AND LIKE MACHINE

Russell E. Benner, Middletown, Conn., assignor to
Remington Rand Inc., Buffalo, N. Y., a corpora-
tion of Delaware

Application March 3, 1932, Serial No. 596,494

17 Claims. (Cl. 197—136)

My invention relates to typewriting and like machines and more particularly to card clamping means for cylindrical platens employed in such machines.

5 One of the main objects of my invention, generally stated, is to provide simple, comparatively inexpensive, and highly effective card clamping means.

A further object of my invention is to provide 10 improved means whereby a plurality of independently controlled card clamps may be employed on a single platen to enable a plurality of cards to be successively clamped in position along the platen without disturbing those already clamped 15 in place, and in order to feed at one movement a plurality of cards arranged side-by-side on the platen and thereby materially increase the speed at which the cards may be written.

Another object of my invention is to so construct and arrange the parts that by reversing 20 the platen end-for-end, the card holding devices may be conditioned so as to change the direction of feed of the cards; a back feed of the cards being effected in one case and a front feed in the other.

A still further object of the invention is to so construct and arrange the parts that independently operable finger pieces that control the opening of the clamps are so situated that ready 30 access thereto may be had by the operator when the platen is in a card receiving position, thereby facilitating the speedy clamping of the cards in place or the withdrawal thereof from the platen, whether the cards are being back fed or 35 front fed.

Still another object of my invention is to so construct the card clamping and controlling means that they may be supplied in separate units, and one or more units may be readily applied to a platen in accordance with the requirements of the user.

To the above and other ends which will hereinafter appear my invention consists in the features of construction, arrangements of parts and 45 combinations of devices set forth in the following description and particularly pointed out in the appended claims.

In the accompanying drawings wherein like reference characters indicate corresponding parts 50 in the different views—

Fig. 1 is a front view of the platen, with parts in section, equipped with card clamping devices of my invention.

Figs. 2 and 3 are enlarged, detail, transverse, 55 sectional views of the same, together with the

feed rolls and paper apron, the section being taken on the line 2—2 of Fig. 1 and looking in the direction of the arrows at said line; Fig. 2 showing a clamp released and Fig. 3 disclosing the parts as they appear in normal position.

Fig. 4 is a front view of a platen equipped with three independently operable card clamps of my invention.

Fig. 5 is a perspective view of parts of a single unit which make up a card clamp and the controlling means therefor; the parts being shown detached from the platen.

Fig. 6 is a sectional view corresponding to Fig. 2 but showing the platen reversed end-for-end for effecting a front feed of a card.

In the present instance I have shown my invention embodied in a platen of a No. 6 Remington Noiseless machine although it is also applicable to the platens of a No. 8 Remington machine, and may in fact be employed in platens 75 of typewriting and like machines generally, wherever found available.

The cylindrical platen, which is designated as a whole by the reference numeral 10, in the present instance comprises an inner metal shell 11 surrounded by a rubber sheath or covering 12. The platen is apertured at 13 throughout the length thereof to receive several series of pins 14. These pins of each separate series are riveted to and project from a sheet metal support or carrier 15 that is preferably angular in cross section to add to the rigidity of the carrier. Each carrier 15 is provided at the ends thereof with ears 16 and 17 that are formed integral with the base portion of the carrier to which the pins 14 are secured. The ears 16 and 17 are pierced to receive a pivot rod 18 that is supported in openings in blocks or hangers 19 riveted at 20 to the inner metal shell 11 of the platen and projecting inward therefrom.

Surrounding each pin 14 is a coiled expansion spring 21 that bears at one end against a carrier 15, and at its opposite end bears against a perforated metal bar 22 through the openings in which the pins extend, it being understood that a separate bar 22 is provided for each clamping unit. Each bar 22 is interposed between the outer ends of the associated coiled expansion springs 21 and the inner side of the metal shell 11 and has a bodily movement with the companion pins during the rocking of their carrier 15 around its pivot rod 18 from the Fig. 3 to the Fig. 2 position and vice versa. It will be understood that each plate or bar 22 constitutes an abutment against which the outer ends of the associated 105 110

springs bear, the bar preventing the springs from entering the enlarged openings 13 in the platen through which the pins 14 pass.

The outer ends of the pins 14 are tapped, as indicated at 23 in Fig. 5, to receive headed screws 24 by which a card clamping plate 25 is detachably secured to the outer ends of the companion series of pins. In practice it may only be necessary to provide a screw 24 for every other pin of a series, as indicated in Fig. 1. It is desirable, however, to employ a comparatively close arrangement of the pins 14 in order that they may constitute an effective abutment against which an edge of a card 26 may bear and be squared, as indicated in Figs. 2 and 3, even when a very narrow card is employed.

The effective force of each series of springs 21 is exerted to normally maintain the companion parts in the Fig. 3 position with the clamping bar 20 pressed against the outer cut-away portion of the platen, indicated at 27, and to firmly hold the leading edge of a card against the platen and cause the card to be fed with the platen either with a back feed, as indicated in Fig. 2, or a front feed, as indicated in Fig. 6. It will be understood that the clamping bars when in the effective position are maintained substantially flush with the outer surface of the platen, so that they cannot engage the front end 28 of the paper apron 29 as the card clamps in a back feed pass said front end 28 in the movement of the clamps in a clockwise-direction, as the parts appear in Fig. 6.

In order to effect a release of each card clamp, I have provided, in the present instance, a separate independently operable finger piece 30 for each unit, and each finger piece in the normal position of the associated parts represented in Fig. 3, has its outer contact face substantially flush with the surface of the platen. Each finger piece moves in an opening 31 provided in the platen and is located outside of the field of the associated card clamp, or any of them, being preferably off-set to the left of the associated card clamp, as indicated in Fig. 1. The relative arrangement of the parts is such that access may be readily had to a finger piece 30, or each of them, when the platen is in the card receiving position, whether the card be back fed or front fed, as indicated in Figs. 2 and 6 respectively. Each finger piece is connected to a stem or plunger 32 pivoted at its lower end at 33 to a control lever 34. I prefer to employ a leaf spring 35 riveted at 36 to each stem 32, the free end of said spring overlapping the associated lever 34 and the pivot 33 thereof, in order to effectively maintain the pivotal connection between the key stem and lever, yet permitting a ready disconnection and reconnection to be effected between these parts when desired.

Each lever 35 is provided with an off-set arm or finger 37 which is adapted to bear against and fulcrum on the inner surface of the platen shell 11. Each lever 34 also is pivoted at 38 to an extension 39 on the ear 17 of the companion carrier 15. This pivotal connection at 38 is on the opposite side of the pivot rod 18 from that where the pins 14 are located. It will be understood therefore that a depression of a finger piece 30 to the Fig. 2 or Fig. 6 position is effective to rock the companion lever 34 and effect a pivotal movement of the associated carrier 15 around its pivot rod 18, thereby swinging the pins 14 carried thereby from the Fig. 1 to the Fig. 2 or Fig. 6 position against the force of the springs 21 and thus release the associated card clamp 25.

The parts of each clamp constitute a single unit, and as many of these units may be employed on a single platen as the character of the work requires. I prefer to employ a plurality of independent carriers 15, say for example three, all mounted on the single pivot rod 18 and each provided with its own individual release key 30 and associated parts, whereby any one card clamp may be released independently of the others. In this manner a plurality of cards may be successively clamped side-by-side on the platen and after a card is clamped in position by one card clamp it is unnecessary to release such clamped card in order to clamp a second and a third card in place. The card clamps are preferably arranged in alignment longitudinally of the platen, as indicated in Figs. 1 and 4, and as hereinbefore indicated as many independently operable card clamps may be employed as are found necessary or the length of the platen employed will permit.

It will be noted that in each instance the finger piece 30 by which a card clamp is controlled is off-set laterally from the field of its card clamp and from the other card clamps as well and does not interfere with the ready insertion of a card in place in any clamp, and all of the finger pieces are readily accessible to the operator when the platen is in a card receiving position, indicated in Figs. 2 and 6. The off-set arrangement of the finger pieces in the face of the platen is clearly indicated in Figs. 1 and 4.

In assembling the parts, each carrier 15, with the parts carried thereby, is introduced into the platen, it being understood that one or both of the usual platen heads 40 is removed at this time. The pins 14 on each carrier are introduced from inside of the platen through the aperture 13 and the associated clamping plate 25 is then secured to the pins, or to some of them, by the screws 24. The pivot rod 18 is introduced endwise through the openings in the hangers and bearing openings in the ears 16 and 17 of the carrier to pivotally support it in place. The associated finger piece 30 which has previously been inserted in the platen is then connected at its pivot 33 to the companion control lever 34. Each unit is assembled in the same general manner.

The usual feed rollers 41 extend through openings in the paper apron 29 and cooperate with the cards 26 as they are fed by the platen and card clamps past said feed rollers, whether the cards be back fed, as indicated in Figs. 2 and 3, or be front fed, as indicated in Fig. 6.

Various changes may be made in the construction, and certain features thereof may be employed without others, without departing from my invention as it is defined in the accompanying claims.

What I claim as new and desire to secure by Letters Patent is:

1. The combination of a cylindrical platen, a plurality of independently releasable card clamps carried by and arranged in alignment along the platen, springs contained within the platen for pressing said clamps separately to clamping position, a separate carrier for each clamp and against which said springs bear, a pivot rod on which said carriers are pivoted, a series of pins on each carrier that project through openings in the platen, one of the card clamps being fixed to each series of said pins, and means including independently operable finger pieces connected to said carriers for independently moving them and said clamps against the force of their springs.

2. The combination of a cylindrical platen

having an inner metal shell covered with rubber, hangers fixed to said shell, a pivot rod or spindle supported by said hangers, a metal carrier pivotally mounted on said rod, a series of pins on said carrier and which project through openings in the platen, a card clamp fixed to said pins, a series of springs that surround said pins and exert their force against said carrier, a finger piece that projects through an opening in the platen, and controlling means intermediate said finger piece and carrier for turning the latter against the force of said springs and releasing the card clamp.

3. The combination of a cylindrical platen having an inner metal shell covered with rubber, hangers fixed to said shell, a pivot rod or spindle supported by said hangers, a carrier pivotally mounted on said rod, a series of pins on said carrier and which project through openings in the platen, a card clamp carried by said pins, a series of springs that surround said pins and exert their force against said carrier, a finger piece, and controlling means intermediate said finger piece and carrier for turning the latter against the force of said springs and releasing the card clamp, said last mentioned means comprising a lever that fulcrums against said metal shell and is connected to said finger piece and said carrier.

4. The combination of a cylindrical platen having an inner metal shell covered with rubber, hangers fixed to said shell, a pivot rod or spindle supported by said hangers, a sheet metal carrier pivotally mounted on said rod, a series of pins on said carrier and which project through openings in the platen, a card clamp fixed to said pins, a series of springs that surround said pins and exert their force against said carrier, a finger piece that projects through an opening in the platen, and controlling means intermediate said finger piece and carrier for turning the latter against the force of said springs and releasing the card clamp, said last mentioned means comprising a lever pivotally connected to and supported by said carrier and which fulcrums against said metal shell, and a plunger pivoted at one end to said lever and carrying said finger piece at the other end thereof.

5. The combination of a cylindrical platen having an inner metal shell covered with rubber, hangers fixed to said shell, a pivot rod or spindle supported by said hangers, a plurality of sheet metal carriers mounted for independent pivotal movement on said pivot rod, a series of pins on each of said carriers, said pins projecting through openings in the platen, a separate and independently movable card clamp connected to pins of each of said carriers, a series of springs that surround the pins of each card clamp, a separate independently operable finger piece for each carrier, and means controlled by each finger piece for moving the associated carrier independently of the others, thereby effecting a release of each card clamp independently of the others.

6. The combination of a cylindrical platen having an inner metal shell covered with rubber, hangers fixed to said shell, a pivot rod or spindle supported by said hangers, a plurality of sheet metal carriers mounted for independent pivotal movement on said pivot rod, a series of pins on each of said carriers, said pins projecting through openings in the platen, a separate and independently movable card clamp connected to pins of each of said carriers, separate spring means for each carrier for independently

pressing the associated card clamp to clamping position, a separate independently operable finger piece for each of said carriers, and an independently operable lever operatively connected to each of said carriers and the associated finger piece for independently moving the associated carrier against the force of its spring means and separately releasing the companion card clamp.

7. The combination of a cylindrical platen having an inner metal shell covered with rubber, hangers fixed to said shell, a pivot rod or spindle supported by said hangers, a plurality of sheet metal carriers mounted for independent pivotal movement on said pivot rod, a series of pins on each of said carriers, said pins projecting through openings in the platen, a separate and independently movable card clamp connected to pins of each of said carriers, separate spring means for each carrier for independently pressing the associated card clamp to clamping position, a separate independently operable finger piece for each of said carriers, and an independently operable lever operatively connected to each of said carriers and the associated finger piece for independently moving the associated carrier against the force of its spring means and separately releasing the companion card clamp, the construction and arrangement of the parts being such that when the platen is reversed end-for-end the clamps may be employed to reverse the direction of the feed of the cards, providing a back feed in one case and a front feed in the other.

8. The combination of a cylindrical platen perforated to receive a series of pins, a sheet metal carrier contained within the platen and provided with ears at the ends thereof to provide a pivotal support for said carrier, a series of pins carried by said carrier and projecting through said perforations, a series of coiled springs that surround said pins and each of which bears at one end against said carrier, a perforated plate within the platen through which said pins pass and against which the opposite ends of said springs bear, a card clamping bar detachably fixed to said pins, a finger piece carried by the platen, and means controlled by said finger piece for rocking said carrier against the force of said springs and releasing said card clamping bar.

9. The combination of a cylindrical platen perforated to receive a series of pins, a sheet metal carrier contained within the platen and provided with ears at the ends thereof to provide a pivotal support for said carrier, a series of pins carried by said carrier and projecting through said perforations, a series of coiled springs that surround said pins and each of which bears at one end against said carrier, a perforated plate within the platen through which said pins pass and against which the opposite ends of said springs bear, a card clamping bar detachably fixed to said pins, a finger piece carried by the platen, and means controlled by said finger piece for rocking said carrier against the force of said springs and releasing said card clamping bar.

10. The combination of a platen having a metal inner shell and an outer rubber covering, said platen being perforated to receive a series of pins, hangers contained within the platen and riveted to said inner shell, a pivot rod supported by said hangers, a sheet metal carrier having ears at the ends thereof pierced to receive said pivot rod, a series of pins riveted to said carrier and projecting through said perforations in the platen, a series of coiled expansion springs surrounding said pins and each of which bears at one end against said carrier, a perforated plate within the platen through which said pins pass and against which the opposite ends of the springs bear, a card clamping bar detachably connected to said pins, a finger piece extending through an opening in the face of the platen outside of the field of said clamping plate, and means controlled by said finger piece for rocking said carrier on its pivot rod against the force of said springs thereby releasing the clamping plate. 80

11. The combination of a platen having a metal inner shell and an outer rubber covering, said platen being perforated to receive a series of pins, hangers contained within the platen and riveted to said inner shell, a pivot rod supported by said hangers, a sheet metal carrier having ears at the ends thereof pierced to receive said pivot rod, a series of pins riveted to said carrier and projecting through said perforations in the platen, a series of coiled expansion springs surrounding said pins and each of which bears at one end against said carrier, a perforated plate within the platen through which said pins pass and against which the opposite ends of the springs bear, a card clamping bar detachably connected to said pins, a finger piece extending through an opening in the face of the platen outside of the field of said clamping plate, and means controlled by said finger piece for rocking said carrier on its pivot rod against the force of said springs thereby releasing the clamping plate. 85

12. The combination of a platen having a metal inner shell and an outer rubber covering, said platen being perforated to receive a series of pins, hangers contained within the platen and riveted to said inner shell, a pivot rod supported by said hangers, a sheet metal carrier having ears at the ends thereof pierced to receive said pivot rod, a series of pins riveted to said carrier and projecting through said perforations in the platen, a series of coiled expansion springs surrounding said pins and each of which bears at one end against said carrier, a perforated plate within the platen through which said pins pass and against which the opposite ends of the springs bear, a card clamping bar detachably connected to said pins, a finger piece extending through an opening in the face of the platen outside of the field of said clamping plate, and a control lever fulcrumed on said inner shell and pivotally connected to said finger piece and carrier and effective on the depression of said key to rock the carrier against the force of said springs and release the card clamping plate. 90

13. The combination of a platen having a metal inner shell and an outer rubber covering, said platen being perforated to receive a series of pins, hangers contained within the platen and riveted to said inner shell, a pivot rod supported by said hangers, a sheet metal carrier having ears at the ends thereof pierced to receive said pivot rod, a series of pins riveted to said carrier and projecting through said perforations in the platen, a series of coiled expansion springs surrounding said pins and each of which bears at one end against said carrier, a perforated plate within the platen through which said pins pass and against which the opposite ends of the springs bear, a card clamping bar detachably connected to said pins, a finger piece extending through an opening in the face of the platen outside of the field of said clamping plate, and a control lever fulcrumed on said inner shell and pivotally connected to said finger piece and carrier and effective on the depression of said key to rock the carrier against the force of said springs and release the card clamping plate, the construction and arrangement of the parts being such that when the platen is reversed end-for-end the clamps may be employed to reverse the direction of the feed of the cards, providing a back feed in one case and a front feed in the other. 95

14. The combination of a cylindrical platen having a plurality of openings that extend through the surface thereof intermediate the ends of the platen, a plurality of independently releasable card clamps carried by and arranged in alignment along and supported from within the platen, said clamps being normally substantially flush with the surface of the platen, springs contained within the platen for pressing said clamps separately to clamping position, and releasing means for releasing said clamps independently of one another comprising a plurality of finger pieces carried by the platen intermediate the ends thereof and rotative with the platen, each finger piece extending through one of said openings in the surface of the platen and being off-set laterally of the field of the associated card clamp to give the operator convenient access to the finger pieces when the clamps are in card receiving position. 100

15. The combination of a cylindrical platen having a plurality of openings that extend through the surface thereof intermediate the ends of the platen, a plurality of independently releasable card clamps carried by and arranged in alignment along and supported from within the platen, a plurality of springs contained within the platen and associated with each card clamp for pressing said clamps separately to clamping position, and releasing means for releasing said clamps independently of one another comprising a plurality of finger pieces carried by the platen and extending through said openings with the surface of the platen and arranged flush with said surface and off-set laterally outside of the fields of the card clamps to give the operator convenient access to said finger pieces when the clamps are in card receiving position, and means contained within the platen for individually shifting each of said clamps against the force of its springs by the depression of the associated finger piece. 105

16. The combination of a cylindrical platen having a plurality of openings that extend through the surface thereof intermediate the ends of the platen, a plurality of independently releasable card clamps carried by and arranged in alignment along and supported from within the platen, said clamps being normally substantially flush with the surface of the platen, a plurality of springs contained within the platen and asso- 110

17. The combination of a cylindrical platen having a plurality of openings that extend through the surface thereof intermediate the ends of the platen, a plurality of independently releasable card clamps carried by and arranged in alignment along and supported from within the platen, said clamps being normally substantially flush with the surface of the platen, a plurality of springs contained within the platen and asso- 115

18. The combination of a cylindrical platen having a plurality of openings that extend through the surface thereof intermediate the ends of the platen, a plurality of independently releasable card clamps carried by and arranged in alignment along and supported from within the platen, said clamps being normally substantially flush with the surface of the platen, a plurality of springs contained within the platen and asso- 120

19. The combination of a cylindrical platen having a plurality of openings that extend through the surface thereof intermediate the ends of the platen, a plurality of independently releasable card clamps carried by and arranged in alignment along and supported from within the platen, said clamps being normally substantially flush with the surface of the platen, a plurality of springs contained within the platen and asso- 125

20. The combination of a cylindrical platen having a plurality of openings that extend through the surface thereof intermediate the ends of the platen, a plurality of independently releasable card clamps carried by and arranged in alignment along and supported from within the platen, said clamps being normally substantially flush with the surface of the platen, a plurality of springs contained within the platen and asso- 130

21. The combination of a cylindrical platen having a plurality of openings that extend through the surface thereof intermediate the ends of the platen, a plurality of independently releasable card clamps carried by and arranged in alignment along and supported from within the platen, said clamps being normally substantially flush with the surface of the platen, a plurality of springs contained within the platen and asso- 135

22. The combination of a cylindrical platen having a plurality of openings that extend through the surface thereof intermediate the ends of the platen, a plurality of independently releasable card clamps carried by and arranged in alignment along and supported from within the platen, said clamps being normally substantially flush with the surface of the platen, a plurality of springs contained within the platen and asso- 140

23. The combination of a cylindrical platen having a plurality of openings that extend through the surface thereof intermediate the ends of the platen, a plurality of independently releasable card clamps carried by and arranged in alignment along and supported from within the platen, said clamps being normally substantially flush with the surface of the platen, a plurality of springs contained within the platen and asso- 145

24. The combination of a cylindrical platen having a plurality of openings that extend through the surface thereof intermediate the ends of the platen, a plurality of independently releasable card clamps carried by and arranged in alignment along and supported from within the platen, said clamps being normally substantially flush with the surface of the platen, a plurality of springs contained within the platen and asso- 150

ciated with each of said clamps for pressing the clamps separately to clamping position, and releasing means for releasing said clamps independently of one another comprising a plurality of finger pieces carried by and rotative with the platen and extending through said openings in the surface of the platen, each finger piece being off-set laterally of the field of the associated card clamp to give the operator convenient access to the finger pieces when the clamps are in card receiving position, the construction and arrangement of the parts being such that when the platen is reversed end-for-end the clamps may be employed to reverse the direction of the feed of the cards, providing a back feed in one case and a front feed in the other.

17. The combination of a cylindrical platen, a plurality of independently releasable card clamps

carried by and arranged in alignment substantially through the length of the platen and supported from within the platen, said clamps being normally substantially flush with the surface of the platen, independently acting springs within the platen for independently pressing said clamps to effective position, and independently operable releasing means for releasing said clamps independently of one another, each card clamp, its springs and releasing means being in the nature of a separate unit, whereby a plurality of cards may be successively clamped in position substantially throughout the length of the platen without disturbing those cards already clamped in place, and whereby a greater or less number of said units may be employed depending on the length of the platen.
